Primary Examiner — Rebecca Tsehay*(74) Attorney, Agent, or Firm* — Oblon, McClelland,
Maier & Neustadt, L.L.P.(57) **CLAIM**

The ornamental design for a case for smokers' accessory, as shown and described.

DESCRIPTION

FIG. 1 is a front, top, and right side perspective view of a first embodiment of a case for smokers' accessory showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a front, top, and right side perspective view of a second embodiment of a case for smokers' accessory showing the new design.

FIG. 9 is a front elevational view thereof.

FIG. 10 is a rear elevational view thereof.

FIG. 11 is a top plan view thereof.

FIG. 12 is a bottom plan view thereof.

FIG. 13 is a right side elevational view thereof.

FIG. 14 is a left side elevational view thereof; and,

FIG. 15 is a front, top, and right side perspective view thereof in an open position.
